UNITED STATES PATENT OFFICE.

RUTH BLOCH OPPENHEIMER, OF NEW ROCHELLE, NEW YORK.

BRASSIÈRE AND DRAWERS.

1,354,207.

Specification of Letters Patent. Patented Sept. 28, 1920.

Application filed September 27, 1919. Serial No. 326,858.

To all whom it may concern:

Be it known that I, RUTH B. OPPENHEIMER, a citizen of the United States, and a resident of the city of New Rochelle, county of Westchester, and State of New York, have invented a new and useful Brassière and Drawers for Stout Women, of which the following is a specification.

The object of my invention is to provide 10 a combined brassière and drawers that may be worn next the skin of the wearer and be light, cool and comfortable in hot weather. This object is accomplished by my invention, one embodiment of which is herein- 15 after more particularly pointed out. This garment takes the place of three garments.

For a more particular description of my 20 invention, reference is to be had to the accompanying drawings, forming a part hereof, in which:

Figs. 2 and 3 are sectional views taken on the lines 2--2 and 3--3 of Fig. 1.

Throughout the various views of the 25 drawings similar reference characters designate similar parts.

My improved brassière and drawers 1 is provided with a back 2 and a front 3 which are identical except that the back 2 has an 30 opening at the top which may be closed by hooks and eyes 5 and the front 3 has a plait 6 which is reinforced at 7 when the top 8 is joined to the bottom 9. The plait 6 allows for alterations due to shrinkage. 35

The crotch 10 is reinforced and the leg 40 openings 11 extend well up at the sides, as indicated. Arm straps 12 are also provided by which the garment is suspended from the shoulders.

From the foregoing it is apparent that my 45 single garment takes the place of two or three ordinary garments and that it is strong, light, durable and cool in hot weather.

Having thus described my invention what I claim is—

A one piece undergarment for stout women composed of a back with a single opening which may be closed by suitable means, 50 which opening is located at the top, a front without an opening, arm straps and leg openings that extend well up at the sides.

RUTH BLOCH OPPENHEIMER.
